UNITED STATES PATENT OFFICE

170,354

SHADOW BOX

George Gast, Chicago, Ill., assignor to Superior Plastics Inc., Chicago, Ill., a corporation of Delaware

Application January 21, 1953, Serial No. 23,206

Term of patent 14 years

(Cl. D33—3)

To all whom it may concern:

Be it known that I, George Gast, a citizen of the United States, residing at Chicago, in the county of Cook and State of Illinois, have invented a new, original, and ornamental Design for a Shadow Box, of which the following is a specification, reference being had to the accompanying drawing, forming a part thereof.

Fig. 1 is a front elevational view of a shadow box showing my new design;

Fig. 2 is a plan view thereof; and

Fig. 3 is a side elevational view thereof.

Fig. 4 is a sectional view thereof taken along the line 4—4 of Fig. 1.

I claim:

The ornamental design for a shadow box or the like, substantially as shown.

GEORGE GAST.
